UNITED STATES PATENT OFFICE.

FRED N. LIVINGSTON, OF SEATTLE, WASHINGTON.

CARBURETER.

1,288,942.

Specification of Letters Patent. Patented Dec. 24, 1918.

Application filed August 27, 1917. Serial No. 188,439.

To all whom it may concern:

Be it known that I, Fred N. Livingston, a citizen of the United States, residing at 1534 W. 58th St., Seattle, in the county of King and State of Washington, have invented certain new and useful Improvements in Carbureters; and I do hereby declare the following to be a full, clear, and exact description of the invention, such as will enable others skilled in the art to which it applies to make and use the same.

This invention relates to internal combustion engines and more particularly to carbureting apparatus therefor. In the operation of many types of internal combustion engines, especially when these latter are mounted upon and utilized for driving motor vehicles, there is a considerable loss of fuel by reason of the fact that when it is desired to slow down the speed of the car or when the car is coasting, it is not practicable in ordinary constructions to entirely cut off the supply of gasoline either in the carburetor of the apparatus or the supply of an enriched vapor to the manifold of the engine. This is because of the absence of any means which may be readily thrown into operation to prevent the induction of gasoline to the carburetor or gasoline vapor into the manifold so that even when coasting or when the car is throttled down and the spark turned off there is drawn into the motor cylinders a quantity of fuel vapor. It is one of the more important objects of the present invention to provide means for readily and temporarily interrupting the flow of enriched vapor mixture through the manifold into the engine cylinder and thus to economize the supply of fuel utilized in the operation of the engine. An advantage derived from my present invention in addition to the material saving in fuel is that the engine may be utilized as a brake to check the speed of the car either when it is being slowed down or when it is running down grade and this results incidentally in a saving to the brake members and increases their effective life.

This interruption of intake of gasoline in the manifold may be accomplished in a variety of ways, as for instance, the inflow of gasoline into the carburetor chamber may be interrupted when desired, or the flow of fuel mixture through the manifold to the engine cylinder may be interrupted obviously with a saving by the elimination of

the inflow of gasoline into the carburetor. In the form of controlling the fuel supply last mentioned in which a device may be mounted in the manifold pipe it is desirable to prevent undue attenuation of the gaseous body in the cylinders of the engine, and therefore it is an object of the invention to provide for the relief of the tendency to form a vacuum by the admission of air directly from the outside when suction to the carburetor is interrupted.

With these and other objects in view as will be rendered manifest to those skilled in the art, and set forth in the following specification, the invention consists in means for interrupting the inflow of gasoline or supply an enriched vapor to the intake manifold of the engine and consists further in the details of the construction, combination of parts and in the organization, the invention being illustrated in different forms in the accompanying drawings in which:

Figure 1 is a side elevation of a motor provided with a carburetor and showing the intake control device and the needle valve control as combined therewith, the motor in Fig. 1 being shown as installed upon a vehicle frame to supply operating power.

Fig. 2 is an enlarged detail sectional view of a carburetor involving means for controlling the inflow of fuel by a valve.

The broad idea involved in my invention is to provide means for interrupting the intake of gasoline for the purpose of preventing the flow of enriched vapor through the intake pipe of a manifold of an internal combustion engine for the purpose of economizing in the consumption of fuel under various emergencies and operating conditions especially where an internal combustion is utilized for driving a motor vehicle. I have therefore devised means capable of ready installation in connection with various types of carbureting apparatuses according to the construction thereof, one form of the invention being adaptable to carburetors having needle or control valves for regulating the flow of gasoline to the carburetor and another form of the invention being applicable to the intake pipe of manifolds in cases where the carburetors are not provided with needle valves as above mentioned. Therefore, in order that my invention may be successfully employed in these various types of structures, I have shown in Fig. 1

means whereby the inflow of gasoline into a carbureter may be controlled, and have also shown means whereby the flow of enriched vapor through the intake manifold pipe 5 may be regulated; these devices both accomplishing the same result.

The invention is shown as applied to an internal combustion engine 2 obviously of any suitable type, the latter here being shown as mounted upon the frame of an automobile 3 and is provided with an intake pipe 4 for the manifold 5. To the lower end of the intake pipe 4 there is connected a carbureter 6 a simple type of which is shown, this being provided with a needle valve 7 operative to open or close the inlet port 8 connected to the gasoline supply pipe (not shown). The needle valve 7 has an upwardly extending stem portion 9 passing through the top of the carbureter, the stem being surrounded by a spring 10 reacting on the carbureter or other suitable support and against the lower side of a head or shoulder 11 on the end of the stem 9. For the purpose of depressing the needle valve against the opening action of its spring 10 there is provided a rod or lever 12 which may be suitably connected to the head 11 in this instance the rod being passed through the dash 13 and provided with a pedal 14 on its outer end to be disposed conveniently to the operator so that the lever may be operated by foot if desired. It is desirable that the open position of the needle valve 7 may be regulated so as to give the best running efficiency by the proper supply of gasoline to the carbureter and engine, and to secure this proper adjustment, an adjusting device in the form of a screw 16 is provided and adjustable in a convenient support or threaded bracket arm 17, the screw having suitable connection with an adjusting rod 18 which may be extended up through the dash and provided with a handle or treadle 19 as may be desired. Obviously the adjusting screw 16 can be turned to any suitable position to bear against the head 11 of the stem 9 of the needle valve and the point of the latter properly disposed according to the condition to permit the normal inflow of gasoline for the formation of a combustible vapor.

From the foregoing it will be seen that the operator when desiring to slow down the speed of the car or when coasting, may entirely cut off the supply of gasoline at the supply port 8 by the application of the foot to the pedal 14 and the closing of the valve 7 against its spring 10, the valve being held closed for any suitable period and then when released by the operator automatically opens to the position as determined by the adjusting device 16.

The interruption of the supply of a combustible vapor to the motor may be achieved

also by the provision of a suitable form of valve here shown as a three-way valve 20 mounted in the intake or supply pipe 4 and having a lever arm 21 to which is connected a push rod 22 extended through the dash 13 and provided with a treadle or handle 23 on its inner end within convenient reach of the operator. The valve 20 is adapted to be normally maintained and automatically returned to open position by the provision of any suitable device as for instance a spring 25 one end of which is connected to the push rod 22 and the other to any convenient fixed part as for instance to the dash 13. So long as the valve 20 is in an open position combustible vapor is drawn by the operation of the engine piston into the cylinder through the supply of air and gasoline at the carbureter; but when the valve 20 is thrown to a position to cut off flow from the carbureter, it will then open communication with a port 20^a leading to the atmosphere outside of the pipe, so that on the combustion stroke of the piston in the motor, air under atmospheric pressure may pass freely into the cylinders 90 of the engine and thus obviate any undue tendency to the formation of a vacuum in the cylinder.

It will be seen that either form of my invention is capable of performing the desired function of interrupting the flow of an enriched vapor to the manifold of the engine if desired, with the resulting material saving of gasoline at the time when a combustible vapor is not desired in the engine.

It is understood of course, that there may be various modifications and changes in the organization, details of parts and the combination of the same without departing from the spirit of my invention and within the limits of the appended claims.

What is claimed as new is:—

1. The combination in a carbureter, of a needle valve for the latter controlling flow of fuel to the air chamber of the carbureter, a spring for normally opening the valve, means for closing the valve, and means independent thereof for regulating the opening of the valve independently of the usual throttle.

2. The combination in a carbureter, of a needle valve for the latter controlling flow of fuel to the air chamber of the carbureter, a spring for normally opening the valve, means for adjusting the valve, and means independent of the adjusting means for the closing the valve independently of the usual throttle, said adjusting means including a lever extended to the operator's station.

3. The combination in a carbureter, of a needle valve for controlling issue of liquid to the carbureter, a spring yieldingly holding the valve open, a manual rod directly connected to the valve to close it against the action of the spring, a stop screw engaging

the valve, and a manual rod jointed to the screw and extending with the other rod to a convenient position for operation by the operator.

5. A carburetor having a spring operated needle valve for controlling the flow of fuel, a manual lever secured to the valve, a set

screw adjustable in a bearing overhanging the valve stem to control the opening of the valve, and a manual lever flexibly jointed to the set screw, whereby the operator may readily set or close the valve.

In testimony whereof I affix my signature:

FRED N. LAVINGSPIK.
